CLAIM

The ornamental design for a photography tripod, as shown and described.

DESCRIPTION

FIG. 1 is a front, left and top perspective view of a photography tripod showing our new design;

FIG. 2 is a left elevational view thereof;

FIG. 3 is a front elevational view thereof;

FIG. 4 is a rear view thereof;

FIG. 5 is a right view thereof;

FIG. 6 is a top plan view thereof;

FIG. 7 is a bottom plan view thereof;

FIG. 8 is a bottom perspective view thereof;

FIG. 9 is an enlarged view of a portion labeled as 9 on FIG. 1; and,

FIG. 10 is an enlarged view of a portion labeled as 10 on FIG. 7.

The long dash-short dash broken lines depict enlargement boundaries that form no part of the claimed design. The evenly broken lines illustrate portions of the article that form no part of the claimed design.

1 Claim, 10 Drawing Sheets
